ATTORNEYS.

WITNESS
R. B. Dyer

UNITED STATES PATENT OFFICE.

WARREN E. STEELE, OF SAN FRANCISCO, CALIFORNIA, ASSIGNOR TO MAY C. STEELE,
OF SAN FRANCISCO, CALIFORNIA.

HINGE.

Application filed September 19, 1922. Serial No. 589,222.

To all whom it may concern:

Be it known that I, WARREN E. STEELE, a citizen of the United States of America, and a resident of the city and county of 5 San Francisco, State of California, have invented a new and useful Hinge, of which the following is a specification.

My invention relates to hinges, and especially to casement sash hinges. 10 One of the objects of the invention is the provision of a hinge for a casement sash which is applicable to a stock frame and sash without the necessity for special milling. Another object of the invention is the 15 provision of a hinge of the character described which will permit the sash to move away from the jamb of the frame and turn into such position that the outside of the glass in the sash may be readily cleansed 20 from the inside.

Another object of the invention is the provision of a hinge which is cheaply manufactured from flat stock, so that a meritorious yet inexpensive hinge is provided.

25 My invention possesses other objects and features of advantage, some of which, with the foregoing, will be set forth in the following description of my invention. It is to be understood that I do not limit myself to the showing made by the said description as I may adopt variant forms of my invention within the scope of the claims.

30 Referring to the drawings: Fig. 1 is a perspective view of a corner of a casement sash and frame to which my hinge has been applied. Sections are omitted to more clearly disclose the structure. Fig. 2 is a diagrammatical view showing the outline of the hinge in plan and indicating the 35 various positions thru which the casement sash to which my hinge is applied may be moved. Fig. 3 is a perspective view of a casement window and frame in which my hinge has been used to mount the sash. 40 Fig. 4 is a perspective view of a casement window and frame in which my hinge has been used to mount the sash. 45 The sash is shown at a point about midway between its extreme closed and open position.

For each sash there is of course a pair of 50 hinges required and each hinge comprises a pair of plates one of which, 2, is provided with a longitudinally extending slot 3. A pin 4 is fixed in an extension 6 of the plate 2. The position of this pin is to one side of and intermediate the ends of the slot 3,

as will be noted from an inspection of 55 Fig. 2.

The other half of the hinge comprises a plate 7 having an extension 8 thereon. In order to simplify the manufacture of my hinge I prefer to make the halves of the 60 hinge identical in outline both as to the main body of the plate and the extension thereon. A pin 9 is fixed on the plate 7 in such position as to engage the end of the slot 3 in the plate 2 when the two plates lie together 65 with the edges in alinement. Plate 7, is formed with a slot 10 extending, in the alined superposed position of the plates, in a direction transverse to the slot 3, and running from the body of the plate 7 out into 70 the extension 8 thereon, preferably being curved substantially as shown in Fig. 2. This slot could be straight and in a direction oblique to the slot 3, in the position of the plates referred to, but I prefer to make 75 it in the form shown in order that the initial opening movement of the sash may be largely a pivotal one without any considerable bodily movement.

In the alined superposed position of the 80 plates, the pin 4, which is fixed in the extension of the plate 2, engages the end of the slot 10 most remote from the slot 3. In other words, each plate is provided with a pin fixed therein and slidably engaged in 85 the slot of the other plate.

One side of the hinge is secured to the upper or lower edge of the sash by flat head wood screws inserted thru suitable holes 11 formed therein. Preferably, the hinge is 90 set into the edge of the sash so that the edge is flush with the lower face of the hinge, but with the thin plates from which I make my hinge this is hardly necessary except in work in which a high degree of 95 accuracy is desirable.

The motion of the sash mounted on my hinge will be readily appreciated from examination of Fig. 2, the sash moving from the closed position to an open position in 100 which the outer surface of the glass of the sash is accessible to one standing inside the room. Thus the window may be readily cleaned without danger to the worker. Because of the frictional resistance occurring 105 between the pin and slot connection of the plates it is found that a sash mounted with my hinge, while readily moved when de-

sired, will not blow shut or open under ordinary conditions, in other words, the window will, ordinarily, stay in the position to which it is adjusted. It is of course understood that in mounting a casement sash the upper and lower hinges must be in substantial alinement.

I claim:—

1. A sash hinge comprising a pair of substantially similar plates adapted to lie in alined superposed position when the sash is closed, one plate having a slot extending longitudinally and the other having a slot extending transversely of said first slot, and a pin fixed in each plate and slidably engaged in the slot of the other.
2. A hinge comprising a pair of similar rectangular plates each formed with a similar lateral extension, one plate having a slot extending longitudinally in the body thereof, and a pin fixed in the extension, the other plate having a curved slot in its extension and engaging said pin, and a pin fixed in said other plate and engaging said first named slot.
3. A casement sash hinge comprising a pair of substantially similar plates, one plate being adapted to be attached to the lower

or upper edge of the sash and the other plate being adapted to be attached to the adjacent portion of the frame, and a pin and slot connection between said plates to permit a simultaneous pivotal and longitudinal bodily movement of one plate and sash carried thereby from substantially end to end of the adjacent plate whereby the sash and plate carried thereby move from a position in which the plates are in superposed alignment when the sash is closed through an arc of more than 90° to a position transverse to the plane of the sash opening and intermediate the sides thereof.

4. A hinge comprising a pair of similar plates, each formed with a similar lateral extension, one plate having a longitudinal slot extending substantially the entire length of the body thereof, a pin fixed in the extension, the other plate having a curved slot extending substantially the entire length of the extension thereof and engaging said pin, and a pin fixed in said other plate and engaging said first-named slot.

In testimony whereof, I have hereunto set my hand.

WARREN E. STEELE.
